UNITED STATES PATENT OFFICE.

WILLIAM H. MAGEE, OF MOUNDSVILLE, WEST VIRGINIA, ASSIGNOR TO FOSTORIA
GLASS CO., OF MOUNDSVILLE, WEST VIRGINIA, A CORPORATION OF WEST VIR-GINIA.

DESIGN FOR A CANDLESTICK.

Application filed February 25, 1926. Serial No. 16,661. Term of patent 14 years.

To all whom it may concern:

Be it known that I, WILLIAM H. MAGEE, a citizen of the United States, residing at Moundsville, in the county of Marshall and State of West Virginia, have invented a new, original, and ornamental Design for a Candlestick, of which the following is a specification, reference being had to the accompanying drawing, forming part thereof. The figure is a perspective view, showing my new design.

I claim:

The ornamental design for a candlestick, as shown.

WILLIAM H. MAGEE.
